UNITED STATES PATENT OFFICE

164,570

GOLF CLUB CONVEYANCE

Frederic S. Grover, Brighton, Philip A. Brandmeier, Pittsford, and James E. Brice, Brighton, N. Y.

Application November 13, 1950, Serial No. 12,948

Term of patent 14 years

(Cl. D14—3)

To all whom it may concern:

Be it known that we, Frederic S. Grover, Philip A. Brandmeier, and James E. Brice, citizens of the United States of America, and residents respectively of the towns of Brighton, Pittsford, and Brighton, in the county of Monroe and State of New York, have invented a new, original, and ornamental Design for a Golf Club Conveyance, of which the following is a specification, reference being had to the accompanying drawings, forming part hereof.

Fig. 1 is a perspective view of the golf club conveyance with the hood in place and with the wheels and handle swung to inoperative position, showing the new design;

Fig. 2 is a perspective view, taken obliquely from the rear, of the golf club conveyance with the wheels and handle swung to normal effective position, with the hood removed;

Fig. 3 is a side elevational view of the convey-

ance with the parts thereof in the same relative positions shown in Fig. 2; and

Fig. 4 is a rear elevational view thereof.

We claim:

The ornamental design for a golf club conveyance, substantially as shown.

FREDERIC S. GROVER.
PHILIP A. BRANDMEIER.
JAMES E. BRICE.
